UNITED STATES PATENT OFFICE

FRANK GASTAN, OF TARENTUM, PENNSYLVANIA, ASSIGNOR TO PITTSBURGH PLATE GLASS COMPANY, A CORPORATION OF PENNSYLVANIA

SHEET HANDLING CLAMP

Application filed June 11, 1931. Serial No. 543,557.

The invention relates to a sheet handling clamp. It is designed primarily to handle plate or window glass, but can be used to advantage in carrying heavy plates of any kind. 5 It has for its objects the provision of a very simple construction which will apply a powerful gripping action to the faces of the sheet when a lifting force is applied to the handle of the device, such gripping action increasing with the weight of the sheet and the lifting force so that no slipping can occur regardless of the weight of the sheet. 10 One embodiment of the invention is illustrated in the accompanying drawings, 15 wherein:

Figure 1 is a perspective view of the device in position of use upon a sheet of glass. Fig. 2 is a plan view. Fig. 3 is a side elevation with the parts in the position occupied 20 when the device is first positioned upon the plate and preliminary to the application of clamping force. And Fig. 4 is a section on the line IV—IV of Fig. 2.

Referring to the drawings, 1 is a sheet of 25 glass and 2 is a lifting device in position of use. This lifting device comprises a handle 3 and a fork consisting of the members 4, 4. Lying between the members 4, 4 are a pair of clamping plates 5, 5 preferably of sheet

30 metal and each provided on its outer face with a pair of oppositely inclined wedges 6, 7 and 6, 7. The inner faces of the plates are provided with resilient sheets 8, 8, such as rubber, to give a more secure grip upon the 35 surface of the sheet 1 and in order to avoid marring the surface of such sheet. Each plate is provided with an outwardly projecting pin 9 which extends through the plate and which is threaded for a short distance 40 back from its head. Nuts 10, 10 serve to secure the pins rigidly to the plates. The outer ends of the pins extend slidably through perforations 11, 11 in the forked members 4, 4.

45 The pivot pins 9, 9 are located closer to

the right hand ends of the plates 8, 8 than to their left hand ends so that the plates normally tilt in a counterclockwise direction, the position indicated in Fig. 3, at which time the corners B of the plates engage the end 50 of the handle, thus limiting their tilting movement. At this time, the plates may be separated a maximum distance and it is in this position that the device is applied to the edge of the sheet to be lifted, as indicated 55 in Fig. 3. A lifting movement upon the handle now rotates the forks in a counterclockwise direction around the pivots 9, 9 so that the inner faces of the forks engage the wedge surfaces of the cam members 6, 6 60 and 7, 7, thus causing the plates to move toward each other and grip the glass therebetween. At this time, the device occupies the position indicated in Fig. 1 and the greater 65 the lifting force applied to the handle 3, the greater the camming force of the fork upon the members 6, 6 and 7, 7, so that the grip upon the plate is increased with the weight 70 of such plate. A more secure engagement between the clamping plates and the glass plate is thus insured. There is no danger of the plates slipping while being carried from one position to another by the clamping devices.

The right hand ends of the plates 5, 5 are 75 secured together by a flexible member 12, preferably of leather, whose edges are secured to the plates by the wedges 7, 7 (held by the screws 13, 13). This member 12 serves 80 to square up the clamping plates with respect to the sheet 1 when the device is first applied to the sheet (Fig. 3), and make it possible for the operator to position and clamp the device with one hand, while the other hand engages the sheet to steady 85 it. The operator merely pushes in on the handle 3 and lifts up on it. The member 12 thus held against the edge of the sheet prevents any upward movement of the clamping plates while the handle is being raised 90

and the plates are being moved toward each other until their faces frictionally engage the sheet.

What I claim is:

- 5 1. In combination in a sheet handling clamp, a handle having a forked end, a pair of clamping plates mounted in said end for movement toward and from each other and for rocking movement in a plane parallel to 10 the faces of the plates, and cam means between the outer sides of the plates and the inner sides of the fork causing the plates to approach each other when the plates are rocked in one direction. 70
- 15 2. In combination in a sheet handling clamp, a handle having a forked end, a pair of clamping plates mounted in said end for movement toward and from each other and for limited rocking movement in a plane 80 parallel to the faces of the plates, and cam means between the outer sides of the plates and the inner sides of the fork causing the plates to approach each other when the plates are rocked in one direction. 35
- 20 3. In combination in a sheet handling clamp, a handle having a forked end, a pair of clamping plates pivoted intermediate their ends in said fork and movable toward and from each other, and a pair of wedge 25 members on the outer side of each plate on opposite sides of their pivots, one of each pair of wedges being inclined in one direction and one of each pair in the opposite direction. 95
- 25 4. In combination in a sheet handling clamp, a handle having a forked end, a pair of clamping plates pivoted intermediate their ends on pivots which are slidable endwise in the fork so that the plates are free 30 to move toward and from each other, and a pair of wedge members on the outer side of each plate on opposite sides of their pivots, one of each pair of wedges being inclined in one direction and one of each pair in the opposite direction. 100
- 35 5. In combination in a sheet handling clamp, a handle having a forked end, a pair of clamping plates pivoted intermediate their ends in said fork and movable toward 40 to move toward and from each other, and a pair of wedge members on the outer side of each plate on opposite sides of their pivots, one of each pair of wedges being inclined in one direction and one of each pair in the opposite direction. 105
- 40 6. In combination in a sheet handling clamp, a handle having a forked end, a pair of clamping plates pivoted intermediate their ends in said fork and movable toward 45 and from each other, and a pair of wedge members on the outer side of each plate on opposite sides of their pivots, one of each pair of wedges being inclined in one direction and one of each pair in the opposite direction, and the pivots being so positioned 50 with respect to the center of gravity of the plates that such plates will swing by gravity to a position permitting maximum separation thereof when the clamp is held in 55 position of use. 115
- 55 7. In combination in a sheet handling clamp, a handle having a forked end, a pair of clamping plates mounted in said end for movement toward and from each 60 other and for rocking movement in a plane 65 120
- 65 8. In combination in a sheet handling clamp, a handle having a forked end, a pair of clamping plates mounted in said end for movement toward and from each 70 other and for rocking movement in a plane 75 125
- 70 9. In combination in a sheet handling clamp, a handle having a forked end, a pair of clamping plates pivoted intermediate their ends in said fork and movable toward 75 and from each other, and a pair of wedge members on the outer side of each plate on opposite sides of their pivots, one of each pair of wedges being inclined in one direction and one of each pair in the opposite direction, and the pivots being so positioned 80 with respect to the center of gravity of the plates that such plates will swing by gravity to a position permitting maximum separation thereof when the clamp is held in 85 position of use. 130

parallel to the faces of the plates, a flexible member connecting the ends of the two plates which are nearest the handle, and cam means between the outer sides of the plates and the inner sides of the fork causing the plates to approach each other when the plates are rocked in one direction.

In testimony whereof, I have hereunto subscribed my name this 14th day of May, 1931.

FRANK GASTAN.
